LAYOUT APPARATUS

Eric S. Guttmann, Rockford, Ill., assignor to The
Ingersoll Milling Machine Company, Rockford,
Ill., a corporation of Illinois

Application February 2, 1942, Serial No. 429,201

14 Claims. (Cl. 33—125)

This invention relates to apparatus for facilitating the laying out of dimensions, patterns, designs, etc., or otherwise marking work pieces.

In the present practice, such layout work is still done by means of simple tools such as gauges, squares, indicators, etc., which are manipulated entirely by hand not only in marking the work piece but in making the measurements necessary to locate various points or lines where machining operations are to be performed. This method relies entirely on hand skill and is necessarily slow and of limited accuracy.

The primary object of the present invention is to reduce the time consumed and increase the accuracy attained in layout work while at the same time reducing the skill required.

A more detailed object is to support a layout tool for accurately measured movements along a plurality of predetermined crossing paths and for engagement selectively with different sides of a work piece.

A further object is to provide a layout apparatus by which dimensions may be indicated or marked on both vertical and horizontal surfaces of a work piece by means of a tool mounted above the work piece.

Another object is to provide a novel layout apparatus which provides for extreme accuracy of tool movement, which is adapted for the handling of heavy work pieces, which renders all sides of the work accessible, and which facilitates loading and unloading of the work pieces.

Still another object is to locate the measuring indicators for the different tool movements in a novel relation to provide for accuracy of their response and to facilitate reading from a single control position.

Other objects and advantages of the invention will become apparent from the following detailed description taken in connection with the accompanying drawings, in which

Figure 1 is a fragmentary perspective view of a layout apparatus involving the novel features of the present invention.

Fig. 2 is a fragmentary plan view of the bridge structure with certain of the parts broken away and shown in section.

Figs. 3, 4, 5, 6, and 7 are fragmentary sectional views taken respectively along the lines 3—3, 4—4, 5—5, 6—6, and 7—7 of Fig. 2.

Fig. 8 is a section taken along the line 8—8 of Fig. 6.

Fig. 9 is a fragmentary plan view of one end portion of the bridge guideway taken along the line 9—9 of Fig. 6.

Fig. 10 is a fragmentary cross-sectional view of one end of the bridge and its support taken along the line 10—10 of Fig. 1.

Fig. 11 is a fragmentary longitudinal sectional view of the bridge, the section being taken along the line 11—11 of Fig. 12.

Fig. 12 is a plan sectional view taken along the line 12—12 of Fig. 11.

Figs. 13 and 14 are sections taken respectively along the lines 13—13 and 14—14 of Fig. 12.

Fig. 15 is a section taken along the line 15—15 of Fig. 14.

Fig. 16 is an elevational view partially in section of a layout tool and its support.

Fig. 17 is a section taken along the line 17—17 of Fig. 16.

Fig. 18 is a schematic view of the operating parts of one of the measuring devices.

Fig. 19 is an elevational view of the control panel.

Fig. 20 is a schematic view and wiring diagram.

Fig. 21 is a longitudinal sectional view of another kind of layout tool and its mounting.

While the invention is susceptible of various modifications and alternative constructions, I have shown in the drawings and will herein describe in detail the preferred embodiment. It is to be understood, however, that I do not intend to limit the invention by such disclosure but aim to cover all modifications and alternative constructions falling within the spirit and scope of the invention as expressed in the appended claims.

Referring now to Fig. 1, the improved layout apparatus comprises generally a stationary horizontal work table 10 and a tool supporting structure composed of three parts movable relative to the table along three perpendicularly related paths and including a main frame or bridge 11 disposed above the table and accurately guided for movement longitudinally thereof, a head 12 movable along the bridge and transversely of the table, and a tool carrier or ram 13 mounted on the head for endwise vertical movement toward and from the table. By supporting the carrier for such three dimensional movement, a layout device or tool 14 on the lower end thereof may be positioned for engagement with any point on the top or at the sides of a work piece resting on the table. To facilitate this, the tool is adapted to be projected either downwardly as shown or laterally in four directions at right angles to each other according to which side of the work is to be marked.

The extent of linear displacement in the three directions is measured by three devices 15, 16, and 17 having indicators respectively operable to indicate the extent of movement of the main support 11 longitudinally of the table, the movement of the head 12 transversely of the table, and the movement of the vertical tool carrier 13 vertically of the table. Power operated means is employed for moving the three supports and is arranged to be controlled from a single panel 18 located in a position from which all of the measuring indicators may be viewed conveniently. Thus, by manipulating control devices on the panel while observing the indicators, an operator may move the layout tool into operative association with any point on the top or sides of the work piece and then perform the layout operation through any length of the work surface.

The table 10 is a heavy metal slab preferably substantially longer than it is wide and supported from a base 19 through the medium of screws 20 or the like which may be adjusted to level the table accurately. T-slots are formed in the top to enable work pieces to be clamped in place in the usual way.

In layout work, measurements must be made with extreme accuracy, a tolerance on the order of a thousandth of an inch being frequently required. It is of the utmost importance, therefore, that the movable tool supporting structure possess substantial rigidity and be guided very accurately. At the same time, the structure must be relatively light in weight so that it may be jogged to accurately defined positions and it must afford convenient access to the work table, not only during marking of the work surfaces but also to facilitate loading and unloading of the work pieces. Also, in order to maintain the necessary accuracy of measurement and guiding of the movable parts, the measuring devices and the coating guide surfaces must be properly enclosed. With these requirements in view, the main frame or bridge 11 is of special construction and is supported and guided at three points, two of which are disposed on opposite sides of the bridge and above normal head height on one side of the table while the third point is on the opposite side of the table preferably below the top of the latter.

The two spaced points of support are provided by an elongated track 21 extending along and spaced outwardly from one side of the table and disposed at a height above the latter such as to afford a workman standing at this side of the table convenient access to work pieces supported thereon. Herein the track comprises a hollow elongated casting 22 bolted to the upper end of three L-shaped posts 23, the short legs of which space the track from the table and abut against and are secured to one side of the table. The upper side of the casting is shaped to receive hardened steel rails 24 and 25 projecting upwardly so as to form in effect a channel.

Cast integral with one end of the bridge is a hollow crossbar 26 projecting equal distances in opposite directions and having at each end an outwardly projecting stud 27 carrying a roller 28 that rides on the upper surface of the rail 24. The widened end of the T-shaped bridge is thus supported at widely spaced points.

The crossbar 26 is guided laterally by the opposed surfaces of the rails 24 and 25 and for this purpose, rollers 29 and 30 (Figs. 2 and 5) engaging the respective surfaces are rotatable on pins 31 eccentrically mounted on studs 32 depending

from ribs 33 near opposite ends of the crossbar and overlying the rail 24. Any suitable means, such as a screw 34, may be provided to hold the rollers 29 and 30 in place after they have been adjusted to take up any transverse play between the crossbar and the track.

A housing 35 of inverted U-shaped section is supported by the rails 24 and 25 to enclose the way surfaces and exclude settling dust or foreign particles. The studs 27 project through a slot 36 in one wall of the housing. The ends of the latter beyond the crossbar are closed by a metal belt 37 (see Figs. 5, 6, and 9) extending around rollers 38 at opposite ends of the casting 22 and within the latter with its ends secured to the crossbar 26 at points 39 (Fig. 2). A sheet metal plate 40 secured to the cross bar closes that portion of the track between the ribs 33.

The third point of support for the bridge is provided in the present instance by the upper surface on a hardened rail 41 mounted on a ledge which is formed by milling a channel 42 (see Fig. 10) in the edge of the table remote from the elevated track 21 above described. Foreign matter is excluded from this way and the latter is protected mechanically by a plate 43 fastened to the table edge and having a depending flange spaced from the channel. The lower end of the bridge leg 44 projects horizontally toward the table and carries a projection 45 extending upwardly between the table and the plate 43. A stud 46 on this extension projects into the channel and through an antifriction bearing carries a roller 47 which rides along the channel. Since no provision need be made for guiding the bridge leg 44 laterally of the way 41, the bridge structure is free to expand or contract with temperature changes, this being permitted by shifting of the roller 47 laterally of the way. The bearing is supported eccentrically on the stud 46 and thus may be adjusted to take up play in the parts or level the bridge.

Provision may be made for bracing the bridge against lateral deflection of the end supported by the single roller 47 and this without interfering with the freedom of movement of the head 12 along the bridge. Herein this is accomplished by tie rods 163 having one end connected to the projecting end of the bridge and the other end secured to one end of the crossbar 26. The rods may be threaded into brackets 164 on the bridge to facilitate adjustment of their lengths.

The bridge thus constructed and mounted is guided very accurately and yet is adapted to move freely without danger of binding as a result of temperature changes normally occurring in an ordinary machine shop. At the same time, the construction facilitates the loading of all kinds of work pieces onto the table, thus, by moving the bridge to one end of the table, one side is entirely open and heavy work pieces may be moved onto the table by means of a crane, this being permitted by virtue of the location of the guide for one end of the bridge below the table level.

The bridge is moved back and forth by means of an electrically driven power operator selectively controllable from the panel 18. It is carried by the bridge and preferably housed within one end portion of the crossbar 26. Herein, the operator includes a reversible electric motor 48 (see Figs. 2 and 7) mounted on the outer side wall of the bar and having one end of its shaft 49 connected through non-locking gearing 50, 70 a normally engaged friction clutch 51 and gears

52 to a vertical shaft 53 which is journaled in the crossbar 26 and carries a pinion 54 on its outer end. This pinion meshes with a rack 55 fastened to the casting 22 immediately below the crossbar. The gearing is such that when the motor is energized, the bridge will be traversed along the table at a relatively rapid rate.

To enable the bridge to be positioned accurately or jogged into a desired position, a similarly mounted reversible electric motor 56 incorporating reduction gearing drives a shaft 51 on which is splined one member 58 of a jaw clutch engageable with the teeth on a member 59 fast on the shaft 49 of the motor 48. A spring 60 acting on a lever 61 normally retracts the clutch member 58 maintaining the clutch disengaged. When the motor 56 is energized, a solenoid 62 is also energized shifting the lever 61 to engage the clutch and drive the gearing 50 and 52 through the intermediary of the motor shaft 49. The bridge is thus advanced at such a slow rate of feed as to permit proper control in the positioning of the bridge. The clutch 51 serves as an overload device to prevent breakage of gears in case the movable parts encounter a work piece unintentionally or engage a positive stop provided at the ends of their ways. Another friction clutch 159 between the clutch 58-59 and the motor 48 protects the gears in the motor 56 while the motor 48 is coasting to a stop.

Disposed between the track rails 24 and 25 and carried on extensions of the ribs 33 of the crossbar are clamping devices indicated generally at 64 which are controlled electrically so as to be released whenever either of the motors 48 or 56 is operating and to be applied when these motors are deenergized. Each clamp includes a friction shoe 65 pivoted at 66 and engageable with the rail 25 upon depression of a lever 67. Such depression is effected by a spring 68 stretched between the upstanding arms 69 of two bellcranks pivoted at 70 and having short arms 71 which bear against opposite sides of the lever 67. A solenoid 72 has its armature 73 connected through toggle links 74 to the arms 69, the arrangement being such that when the solenoid is energized, the toggle is straightened and the arms 69 swung apart to release the clamping shoe. As shown in Fig. 2, there is a clamping device at each end of the crossbar 26 so that the clamping forces are of substantially the same magnitude and direction and act on the bar at points equidistant from the bridge 11 which therefore is not displaced under these forces.

The movements of the bridge along its guideways are registered by the measuring device 15 above referred to and registered on a dial or scale 18 which is supported by one end of the bridge crossbar 26 preferably adjacent the bridge and faces toward the control panel 18. As shown in Fig. 18, the indicator includes wheel type revolution counters 15 and 16 for measuring inches and tenths thereof and a pointer 77 coaxing with the stationary scale 78 to read in thousandths of an inch. The wheels and the pointer are actuated through appropriate gearing 79 mounted within a casing 80 (Fig. 2) which is supported in a recess 81 in the crossbar 26. Projecting from the end of the casing 80 is a shaft 82 which between the rails 24 and 25 carries a drum 83 around which a flexible line or tape 84 is wound helically. One end of the tape is attached to the drum at 85, while

the unreeled portion of the tape rests on the upper surface of the casting 22 (see Figs. 2 and 9) and its free end is attached to the casing 22 at 185 beyond the limit position to which the drum is moved. This point of attachment is so located with reference to the drum axis that the unreeled portion of the tape is always maintained at a constant angle α relative to a perpendicular to the drum axis (Fig. 18), such angle being equal to the helix angle of the wound portion of tape. A motor 86 constantly energized tends to turn the drum and the indicating elements in a direction to wind up the tape, its torque being overcome when the bridge is moved by the motors 48 and 56 in a direction to unwind the tape. By inclusion of a friction clutch 88 in the drive train, the pointer and wheels of the indicator may be reset to zero without disturbing the tape tension. This may be effected by turning a knob 89 on the pointer shaft and a knob 90 for resetting the wheel counter in the usual way or by remote control of a motor connected to the reset mechanism. A guard plate 87 (Fig. 6) is supported from the ribs 33 beneath the rollers 28 and 29 and the clamp 64.

With a measuring device of the above character with its drum and tape enclosed in the manner above described, it is possible under ordinary shop conditions to measure the movements of the bridge 11 with an accuracy of less than one thousandth of an inch. Moreover, by virtue of the light construction of the bridge and the action of the clamps 64, it is possible to jog the bridge through very fine increments and, by observing the pointer 77, to position the bridge with extreme precision while standing at the control station across the table.

Referring now to Figs. 1 and 11 to 15, the head 12 is a casting of inverted U-shape (see Fig. 14) fitting over the bridge 11 which is a hollow casting of generally square cross-section. Beneath the bridge, the lower edges of the head casting are connected by a plate 12a. A novel antifriction mounting is provided to support and guide the head in its movement along the rail. This mounting comprises spaced balls 92 and opposed converging way surfaces 93 and 93a constituting ball raceways and respectively formed on rails 94 and 95 respectively seated in grooves in the top of the bridge and the under side of the head casting 12. Each ball is held in recesses in a pair of links 96 which are pivotally connected to adjacent links to form an endless flexible cage whereby the balls are held in spaced relation. Beyond the ends of the head ways, the balls ride in grooved pulleys 97 rotatable on shafts 98. The latter are supported at opposite ends by spaced brackets 99 projecting rigidly from opposite sides of the head and enclosed by sheet metal housings on top of the head.

To exclude dust and foreign matter from the bridge ways 93 beyond the head, a belt 100 is extended around rollers 101 and 102 on the head and is attached at its ends to remote points 103 (see Figs. 1 and 3) of the bridge 11. The rollers 101 and 102 are positioned so that the end portions of the belt rest in a groove 100a above the rail 94 and exclude dirt and foreign matter from the latter. As the head moves along the bridge, one of these portions is lengthened and the other is shortened, the intermediate portion of the belt being flexed around the rollers 70 as the head moves. That portion of the belt

between the rollers 101 is enclosed by a housing 102.

To hold the head against upward displacement, rollers 104 (Figs. 11 and 14) spaced apart longitudinally of the bridge are rotatably supported by lugs 105 on spring plates 106 which are fastened to the plate 12^a and bent so as to urge the rollers against the under surface of a hardened rail 107 seated in and extending along the underside of the bridge 11. By such pre-loading, the head is held down against the bridge and any lifting force applied to the head is counteracted. Rollers 108 rotatably supported by the plate 12^a to turn on vertical axes bear against opposite sides of the rail 107 and thus serve to guide the lower end of the head against displacement laterally of the bridge. The rollers 108 are mounted eccentrically to permit of adjustment in locating the head 12 accurately.

The head is moved along the bridge at fast or slow speed by an electric operator of the character above described having its parts correspondingly numbered with the exponent *a*. This operator includes motors 48^a and 56^a mounted on the top of the head casting as shown on Figs. 12 and 14. The motors are energized under the control of switches on the panel 18 and are operable through gearing 50^a to drive two meshing gears 112 journaled in the top part of the head 12. Beneath this plate, the shafts of these gears carry pinions 113 meshing with racks 114 on the top of the bridge. By duplicating the racks and pinions, the resultant force applied to the head to feed it along the bridge is directed along the longitudinal center of the bridge and guideways so that the feeding force does not tend to twist the head in its mounting on the bridge.

A clamp 64^a (see Fig. 13) similar in construction to the clamps 64 above described is provided for locking the head 12 to the bridge when the motors 48^a and 56^a are deenergized, the parts being mounted on and disposed above the top of the head casting. In this case, the arms 71^a of the bellcranks actuate plungers 115 guided in the casting 12 with their lower ends adapted for engagement with surfaces 116 on the bridge.

Movement of the head along the bridge is measured by the device 16 above referred to, which device is of the same construction as the device 15 previously described, and its parts bear the same reference numbers with the addition of the exponent *a*. To separate its indicator from the others, the operating parts are preferably mounted at the end of bridge 11 near the leg 44 and on the same side of the bridge as the bridge indicator 15. As before, the operating parts of the measuring device are disposed within a sub-housing 80^a behind which is the drum 83^a around which part of the tape 84^a is wound. The unreeled portion of the tape extends along a channel 117 (Figs. 12 and 14) formed along the rear side of the bridge 11 and its end is attached at 119 to a holder 118 projecting into the channel and rigid with the rear wall of the head casting 12. The width of the channel is such as to allow for cross traveling of the tape as it leaves the drum inwinding and unwinding. The tape channel is suitably sealed to exclude dirt as by a belt 120 having its ends secured to the tape holder 118 and extending in a continuous loop around pulleys (not shown) at opposite ends of the channel, the open edge of which is closed at all times. The opposite run of the belt is disposed at the root of the channel.

Projecting forwardly from the front of the head casting 12 are two vertically spaced brackets 121 and 122 bored to provide guideways 123 in which the ram 13 slides endwise. The ram is held against rotation by a key 124 (Fig. 12) mounted on the upper bracket and seating in a longitudinal groove 125 in the ram. The bottom of this groove is engaged by the shoes 126 (Fig. 15) of a clamp 64^b which is constructed and operates in the same way as the clamps 64 and 64^a previously described, the parts bearing similar reference numerals to which the exponent *b* has been added.

The operator for raising and lowering the ram is of the same construction as the bridge and head feeding operators and its parts are given corresponding references with the addition of the exponent *b*. This operator is mounted on the top of the head casting 12 on the side of the ram opposite the head operator and within a cover or sub-housing 128. The driven shaft 53^b of the operator is disposed horizontally and carries a pinion 54^b meshing with rack teeth 130 on the front of the ram. The motors 48^b and 56^b are controlled from the panel 18 and the solenoid 72^b is energized to release the clamp 64^b when either motor is running.

The parts of the measuring device 11 (see Figs. 14 and 15) are in a casing 80^b projecting horizontally into the sub-housing 128 between the brackets 121 and 122 on the lower one of which it is supported. The indicators 75^b, 76^b, and 77^b are exposed on the side of the head facing the control panel. Thus, the indicators of all three of the measuring devices are conveniently visible by an operator standing adjacent the bridge near the control panel 18. This applies to each position of the bridge along the table since all three indicators are mounted to move with the bridge. The indicators are quite widely spaced thereby minimizing the possibility of confusion as to which motion is registered on each indicator. Owing to the slow rates of the movements imparted to the bridge, the head, and the ram by operation of the slow feed motors, the pointers and the scale graduations are plainly observable.

The drum 83^b is disposed adjacent the ram and the unreeled portion of the tape is extended upwardly along the ram and fastened at 131 to the top of the latter, proper provision, of course, being made for cross traveling of the tape in winding and unwinding. A tubular housing 132^b upstanding from the head encloses the upper end of the ram and the tape.

Provision is made for counterbalancing the excess weight of the ram 13 and other parts which are disposed in front of the bridge 11 and tend to twist the head in its mounting on the bridge ways. Herein, the counterweight comprises a block 161 of metal fastened to the side of the head casting 12 on the side of the bridge opposite the ram. As a result of such counterbalancing, no unbalanced force is exerted on the head supporting ways other than the reactionary forces resulting from engagement of the marking tools with the work.

Provision is made for mounting various devices 14 used in layout work on the lower end of the ram 13 and for projection of these devices in various directions for operation on different surfaces of a work piece on the table. These devices may comprise prick punches, indicators for determining zero points, centering drills, and different kinds of marking tools, any of which may be operated electrically and controlled by a push button 160 on the control panel. The mounting

of a scribe tool is illustrated in Figs. 1, 16 and 17. This tool is carried by a holder 132 which is adjustable about a horizontal axis 133 to project the tool point either downwardly as shown in full lines in Fig. 16 or horizontally as shown in dotted outline. Herein, the holder comprises two spaced plates 134 rigidly connected and pivoted on a shouldered stud 135 projecting horizontally from a vertical plate 136 on the lower end of a shank 137. The latter may, as shown, be formed with a tapered upper end 138 received in a correspondingly tapered axial recess 139 in the lower end of the ram 13.

Between the plates is rod 140 of resilient material having one end clamped rigidly to the plates by screws 141. From this point of anchorage, the rod extends downwardly and upwardly to form one loop and then downwardly to form a second loop. The free end of the rod is straight and aligned with the ram axis projecting beyond the plates for attachment thereto of a collar 142 in which the tool 14 is held by a set screw 143. While this mounting of the tool is relatively rigid and the point is positioned accurately, the tool is adapted, by flexing of the loops, to yield axially or laterally in the plane of the rod. At the same time, it is accurately guided by the plates 134 against sidewise movement. Thus, the tool 14 will ride over the surface of a rough casting without the supporting parts being stressed appreciably. A pin 144 on one plate is adapted to be projected through a hole 144^a in the other plate and thus lock the plates together with the tool projecting downwardly exactly vertically and preferably in alignment with the axis of the ram. By removing the pin, turning the plates and replacing the pin in the other hole, the tool will be projected horizontally as shown in dotted outline in Fig. 16 and at right angles to the ram, being thus adapted for operative engagement with the top surface on the work piece.

The holder 132 is mounted detachably on the lower end of the ram for selective adjustment to predetermined angular positions around the ram axis. Four such positions are provided for in the present instance, these being parallel with the paths of movement of the head 12 along the bridge and of the bridge along the table. While this adjustment may be obtained in various ways, it is accomplished herein by forming axially facing notches 145 in the lower end of the ram each adapted to receive a pin 146 projecting from the upper surface of the shank flange in position. The notches are spaced ninety degrees apart in the present instance and the center lines of the diametrically opposite notches are parallel to the path of movement of the bridge in one case and the path of the head 12 in the other. Thus, by adjusting the shank so that the pin 146 projects into the different notches, the tool 14, when extending laterally of the ram, may be conditioned for marking any one of four vertical side surfaces of a work piece either by movement vertically or horizontally. In each case, the selected position of the shank will be such that the tool will yield, as permitted by bending of the rod 140, in the direction of the motion. This also applies to positioning of the tool for operation on the top surface of the work piece.

After such angular adjustment, the tool holder is clamped to the ram, in this instance, by turning a collar 146'. This is formed at opposite ends with right and left hand threads engaging complementary threads on the shank 137 and the ram. As the collar is turned in one direc-

tion, a shoulder on the shank is tightened against the ram end, thereby locking the tool holder in a definite axial position relative to the ram and other parts.

Means is provided for enabling an operator standing adjacent the control panel 18 to bring the tool 14 just into contact with a surface of the work. This means includes an indicating light 148 on the panel 18 energized and deenergized under the control of an electric circuit which extends through the tool and the work piece (see Fig. 18), the collar 142 being composed of insulating material. If desired, suitable relay or amplifying means may be provided so that the full lamp current need not be carried through the points of contact between the tool and the work. Selection of the machine element to be moved is made by turning a knob 153 to actuate a three position switch 154 by which the push buttons are associated with the ram, head, or bridge motors. The direction of operation of the selected motor is determined by the position of a switch 155 having two positions.

Preferably, the slow and rapid motions of the different tool supporting elements, that is, the bridge, the head and the ram, are controlled by a common pair of push button control switches 150 and 151 (see Figs. 19 and 20) thereby insuring that the tool may be moved along only one path at a time. These switches, the six motors, their clutch solenoids, and the three clamps may be connected as shown in Fig. 20. Interlock switches 150^a and 151^a are provided to prevent any possibility of the motor 56 being started while the motor 48 is running.

With the apparatus above described, it will be apparent that a layout tool mounted on the ram 13 may be located with extreme accuracy at any point in the space above the work table and below the bridge. That is, it may be moved longitudinally and transversely of the table to establish a location in a horizontal plane, and the ram may be raised or lowered to determine the third dimension. The extent of motion in each direction may be gauged accurately by observing the proper one of the measuring devices and by operating the slow feed motor of the selected element so as to jog the tool to the desired point in each direction.

For punching drill hole centers, a tool holder 165 (Fig. 21) carrying a prick punch 165^a may be substituted for the scribe holder 132 on the ram 13, the holder preferably incorporating a self-contained power unit for actuating the punch. In the present instance, the holder comprises a tube 166 closed at its end by a bushing 167 in which slides a headed shank 168 carrying the punch. A hammer 169 slidable in a bore 170 is urged toward the shank by a compression spring 171 seated in a plug closing the upper end of the tube. A shoulder 172 on the hammer is engaged by a cam 173 fast on a shaft 174 which is driven through reduction gearing 175 by an electric motor 176 on one side of the tube. In each revolution of the cam, the hammer is retracted compressing the spring and then is released as the tip of the cam passes the shoulder 172. The hammer is projected against an anvil 180 on the shank 168 and the blow thus struck on the anvil 180 causes the punch to indent the work. The punch is normally held in the position shown by a resilient ring 181 engaging a shoulder 182 on the shank.

Energization of the motor 176 may be controlled from a remote point on the control panel by de-

pressing the push button switch 160. The operator gauges the duration of switch closure so that ordinarily only one blow is struck. Since the energy for striking the blow is derived from means carried by the holder, the position of the punch point is not disturbed.

For punching the top of a work piece, the holder is mounted on the ram as shown in Fig. 21. To extend the punch laterally of the ram, a shank 171 projecting from the side of the tube 166 is fitted into the ram with a pin 178 entering one of the notches 145 determined by which wall of the work is to be operated on. It will be seen that the punch and scribe holders 132 and 164 are mountable interchangeably on the ram and are adapted for projection of the tools vertically or in a plurality of horizontal directions. The constructions are so correlated that the different tool tips occupy the identical positions relative to the ram when mounted in corresponding positions. This permits of interchanging tools for operation on the same work piece without resetting the measuring device for a new reference point.

To explain briefly a typical operation of the apparatus, let it be assumed that a line extending transversely of the table is to be scribed on the top of a work piece. The latter would be placed on the table and squared up in the usual manner. By manipulation of the control and selector switches, the tool point would be brought into contact with a previously determined reference point on the work piece. All of the indicators 15, 16, and 17 would then be set at zero through the medium of their reset knobs 89 and 90. To position the tool for marking the line, the control switches are operated to move the tool first longitudinally and then transversely of the table in order to locate it in two dimensions in a horizontal plane above the work, the location being at one end of the line to be described and determined by the reading of the two indicators 15 and 16. Next, the ram is lowered until the scribe point comes in contact with the work as indicated by lighting of the signal lamp 148. The tool is now set for marking the work piece which is effected simply by traversing the head 12 in the proper direction along the bridge. The resilient rod 140 yields both vertically and laterally in the direction of movement to permit the point to pass over any irregularities in the work surface.

From the foregoing, it will be observed that in spite of the substantial size of the apparatus and its adaptability for use with large as well as small work pieces, it is capable of precision work. That is to say, each movable part is accurately guided along ways which are enclosed and fully protected from foreign material. The same is true of the drum and tape of each measuring device which is accurate to within a thousandth of an inch over a range of several feet. The movements necessary to layout all sides and top of a work piece are all incorporated in the tool mounting or bridge structure which is very rigid and yet is light enough in weight to enable its motion to be arrested in a precise position under the push button motor control.

I claim as my invention:

1. A layout machine comprising, in combination, a stationary horizontal work support, a stationary guideway disposed above and extending along one side of said support, a second stationary guideway extending along the opposite side of said support and underlying a part thereof

so as to be protected by such part, an elongated member engaging said first guideway along a substantial length thereof and guided thereby for endwise movement, an L-shaped bridge having one leg extending horizontally across said support and rigidly joined to said member intermediate the ends thereof, the other leg of said bridge being upright and engageable at its lower end with said second guideway, a head supported by and slidable along said horizontal leg, and a layout tool mounted on said head for engagement with a work piece on said support during movement of the head along said bridge or during movement of the bridge along said guideways.

2. A layout machine comprising, in combination, a stationary horizontal work support, a stationary guideway disposed above and extending along one side of said support, a second stationary guideway extending along the opposite side of said support adjacent the top of the latter, an elongated member engaging said first guideway along a substantial length thereof and guided thereby for endwise movement, an L-shaped bridge having one leg extending horizontally across said support and rigidly joined to said member intermediate the ends thereof, the other leg of said bridge being upright and engageable at its lower end with said second guideway, and a head supported by and slidable along said horizontal leg and carrying a layout tool engageable with a work piece on said support during movement of the head along said bridge or during movement of the bridge along said guideways.

3. A layout machine comprising, in combination, a stationary horizontal work support, a stationary guideway disposed above and extending along one side of said support, a second stationary guideway disposed below said first guideway and extending along the opposite side of said support, an L-shaped bridge having one leg extending horizontally across said support and slidable along said first guideway, the other leg of said bridge being upright and engageable at its lower end with said second guideway, and a head supported by and slidable along said horizontal leg and carrying a layout tool adapted for engagement with a work piece on said support.

4. A layout machine comprising, in combination, a stationary horizontal work support, a horizontal bridge disposed above and extending transversely of said support, stationary ways guiding said bridge for lateral movement along said support, a head mounted on said bridge and guided thereby for movement transversely of said support, a layout tool carried by said head and engageable with a work piece on said support during movement of said bridge or of said head along the bridge, two drums rotatably mounted on said bridge, flexible lines wound around said drums with their free ends respectively connected to said head and to a point which is fixed relative to said support, and indicators actuated by rotation of the respective drums to register the movements of said head and bridge.

5. Layout apparatus comprising, in combination, a stationary table, a bridge extending transversely of the table and supported above the latter for bodily movement longitudinally of the table, a head mounted on and slidable along said bridge, a device carried by said head and adapted to perform a layout operation on a work piece supported on said table, and two measuring devices having rotary indicating members rotatably supported on opposite end portions of said bridge, said devices having means respec-

tively connected to said head and to a stationary point and operable during transverse movement of the bridge and movement of the head along the bridge to actuate the respective indicators.

6. Layout apparatus comprising, in combination, a stationary table, a bridge extending transversely of the table and supported above the latter for bodily movement longitudinally of the table, a head mounted on and slidably along said bridge, a member mounted on said head for movement toward and away from said table and carrying a device adapted to perform a layout operation on a work piece supported on said table, two measuring devices having rotary indicating members rotatably supported on opposite end portions of said bridge, said devices having means respectively connected to said head and to a stationary point and operable during transverse movement of the bridge and movement of the head along the bridge to actuate the respective indicators, and a third measuring device having a rotary element mounted on said head and actuated by means attached to said member.

7. Layout apparatus comprising, in combination, a stationary table, a bridge extending transversely of the table and supported above the latter for bodily movement longitudinally of the table, a head mounted on and slidably along said bridge, a member mounted on said head for movement toward and away from said table and carrying a device adapted to perform a layout operation on a work piece supported on said table, three measuring devices having rotary indicating members mounted for movement with said bridge and visible by an operator in a control position adjacent the bridge, and means operable to actuate the respective indicating members during movements of said bridge, said head, and said member.

8. In layout apparatus of the character described, the combination of a horizontal bridge having a ball raceway along its top extending longitudinally thereof, a tool head including a frame having a raceway extending along said first raceway, a series of balls part of which ride in said raceways, a flexible endless cage holding said balls in spaced relation and rotatably supported on said head, a belt extending along said bridge and covering said first raceway, and means on said head guiding the intermediate portion of said belt around said cage to enclose the cage and balls.

9. In layout apparatus of the character described, the combination of a horizontal bridge having ways along its top extending longitudinally and defining a straight V-groove, a tool head including a frame having a V-groove facing and extending along said first groove, a series of balls part of which ride in said groove, a cage holding said balls in spaced relation and in an endless series, and pulleys supporting said cage and rotatably mounted on said head to turn about axes extending transversely of said groove.

10. In layout apparatus of the character described, the combination of a horizontal bridge having a longitudinal V-groove along its top, a head carrying a layout tool and comprising a frame encircling said bridge and having a groove coacting with said first groove to provide a ball

raceway, balls in said raceway, and antifriction means between said frame and the under side of said bridge holding said head against raising and serving to guide the head laterally of the bridge.

11. Layout apparatus comprising, in combination, a stationary work table, a bridge mounted above said table for transverse movement therewith, a head slidable along said bridge in a perpendicular direction, a member mounted on said head for vertical movement toward and away from said table, a holder supported on the lower end of said member for selective adjustment around a vertical axis, means on said holder and member interengageable in four different positions of said holder corresponding to the permissible directions of movement of said head, and a layout device mounted on said holder for selective adjustment to positions for adapting the device for operation on the top or a vertical side surface of a work piece on said table when said holder is disposed in any one of said four positions.

12. Layout apparatus comprising, in combination, a stationary work table, a bridge mounted above said table for transverse movement therewith, a head slidable along said bridge in a perpendicular direction, a member mounted on said head for vertical movement toward and away from said table, a holder supported on the lower end of said member for selective adjustment to positions corresponding to any one of the four directions of permissible movement of said head, and a layout device mounted on said holder for selective adjustment relative to the holder to positions for adapting the device for operation on the top or a vertical side surface of a work piece on said table.

13. A layout machine comprising, in combination, a stationary horizontal work support, two stationary parallel ways extending along opposite sides of said support, one being disposed substantially above said support and the other being substantially above said support and the other being adjacent the support, a rigid bridge member extending transversely of said support substantially above the latter and engaging one of said ways at zones spaced from the bridge on opposite sides thereof, said bridge engaging the other way at a single zone disposed adjacent said support and below the said first zones whereby to provide a three point support for the bridge, and a layout device carried by said bridge for engagement with a work piece on said support.

14. A layout machine comprising, in combination, a stationary work support, two stationary parallel ways extending along opposite sides of said support, a rigid bridge member extending transversely of said support substantially above the latter and engaging one of said ways at zones spaced from the bridge on opposite sides thereof and the other way at a zone adjacent said support, a layout device carried by said bridge for engagement with a workpiece on said support, interengaging feed elements one being stationarily mounted adjacent said first guideway and extending along the latter, the other feed element being mounted on said bridge and engaging the first element between said spaced zones of engagement, and power driven means for driving one of said elements to cause said bridge to be advanced along said work support.

ERIC S. GUTTMANN.
